UNITED STATES PATENT OFFICE.

ADOLF G. STAPEL, OF MONTGOMERY, ALABAMA.

HOT-WATER HEATING SYSTEM.

1,094,757.

Specification of Letters Patent. Patented Apr. 28, 1914.

Application filed July 13, 1912. Serial No. 709,250.

To all whom it may concern:

Be it known that I, ADOLF G. STAPEL, a citizen of the United States, residing at Montgomery, in the county of Montgomery and State of Alabama, have invented a new and useful Hot-Water Heating System, of which the following is a specification.

This invention relates to hot water heating systems.

Hot water heating systems have in the past been known either as one pipe or two pipe systems, and while a strictly one pipe system of hot water heating is impossible, since the radiators must always have two connections, or else there would be no circulation whatever, or at least a very sluggish movement of the water, it has been found in practice that a so-called one pipe main will give good results on account of the circulation being positive and the water being carried through the entire main at about a uniform velocity.

In a hot water heating system with a one pipe main, all the radiators are supplied from the top of the main and the return pipes from the radiators are connected into the side of the main. While this arrangement, as stated above, has given good results, it has the disadvantage of mixing the cooler return water from the radiators with the hot water coming from the boiler, and therefore it is always necessary with a one pipe main to make the same very large, or else the last radiators on the circuit will receive water of considerably reduced temperature.

With the two pipe system of hot water heating, the supply water is kept entirely separated from the return water, but as is well known from practical demonstrations, the velocity in the mains of a two pipe system varies considerably and frequently the radiators at the end of the mains are only having a very sluggish circulation, due to the short circuits which are produced through the radiators nearest the boiler.

From the foregoing considerations, it will be seen that both the one pipe and the two pipe systems are more or less defective and uncertain as to uniform results, especially when hot water has to be conducted to radiators at a great distance.

The object of the present invention is to eliminate the disadvantages of both the one and the two pipe systems, and to a great extent to combine the advantages of both.

In the accompanying drawing, forming

part of this specification, Figure 1 is a perspective view of a hot water heating system arranged in accordance with the present invention; Fig. 2 is a vertical section through three floors of a house equipped with the system; and Fig. 3 is a diagrammatic view showing a slight modification of the system.

Like reference numerals indicate corresponding parts throughout the several figures of the drawings.

The reference numeral 1 indicates the boiler which may be of any suitable form and construction. Extending upward from the boiler 1 is a riser 2 which leads into the lower end of an accelerator 3. The accelerator 3 may be of the type illustrated in United States Patent No. 980,360, granted to me January 3, 1911, or of any other suitable type. Leading from the accelerator 3 is a riser 4 which extends preferably to a high water level in the system. The riser 4 connects with a horizontal pipe 5 above which is mounted the expansion tank 6. The tank 6 is connected with the pipe 5 by the pipes 7 and 8. The water level of the system is located just above the lowest portion of the expansion tank 6. Extending downward from the horizontal pipe 5 is a flow pipe 9. The flow pipe 9 connects with a horizontal flow pipe 10 which extends around the lower floor of the house, preferably at a uniform level. Located below the flow pipe 10 is a return pipe 11. The return pipe 11 is connected at 12, as best indicated in Fig. 3, with the lower portion of the flow pipe 10 at a point in advance of the foremost radiator A or its feed pipe. The radiator A is fed with hot water from the flow pipe 10 by a feed pipe 14 which extends into the upper end of the radiator as shown in Fig. 3. The cold water from the radiator A passes through an exit pipe 15 into the return pipe 11. The radiator B which is indicated in Fig. 3 as being located on the second story of the building, is likewise fed from the flow pipe 10 through a pipe 14, the cooler water from the radiator passing through the pipe 15 to the return pipe 11. In advance of each feed pipe of the radiators A, B, and so on throughout the series, the lower portion of the flow pipe 10 is connected with the return pipe 11 by means of a cross-over pipe 16.

At a point beyond the last radiator the flow pipe 10 extends downward as indicated at 17 and connects with the return pipe 11.

The return pipe 11 is then extended, as indicated at 18, back toward the boiler, after which it is carried upward in a vertical direction, as indicated at 19, and then in a 5 horizontal direction, as indicated at 20, and then downwardly, as indicated at 21, to the bottom of the boiler 1. The upper portion 20 of the return pipe is connected by a pipe 22 with the top of the expansion tank 6, so 10 that any vapor which may accumulate in the expansion tank will be fed into and absorbed by the cooler water in the return pipes 19, 20 and 21.

From the foregoing description, it will be 15 seen that the flow and return pipes parallel each other around the lower floor of the building, the return pipe being in a lower water level than the flow pipe, said return pipe and flow pipe being connected with each 20 other at points on opposite sides of the radiator zone, and that each radiator has a feed pipe connected with the main flow pipe and an exit pipe connected with the return pipe.

25 Constructed as described, the operation of the system is as follows: The water in the boiler 1 preferably is heated above the steam formation point and passes upward through the accelerator 3, where it is converted into 30 an emulsion of steam and water. This hot water passes upward through the pipes 4 and 5 and downward through the pipe 9 to the horizontal flow pipe 10. The flow pipe 10 contains hot water and this hot 35 water remains in said flow pipe 10 throughout its entire length, by reason of the fact that said flow pipe 10 is in a higher water level than the return pipe 11. The hot water in the flow pipe 10 passes through the 40 various feed pipes 14 to the upper ends of the radiators no matter on what floor the radiators may be located. The cooler water from the radiators passes through the exit pipes 15 to the return pipe 11 and by reason 45 of the lower water level of said return pipe 11 the cooler water remains in said return pipe and does not mix with the hot water in the flow pipe 10. In the event that all of the radiators are cut off, the cross-over 50 pipes 16 still permit a normal circulation in the system. These cross-over pipes 16 permit any water of a relatively low temperature in the flow pipe 10 to settle into the return pipe 11 without having to pass 55 throughout the entire length of said flow pipe 10 until it reaches the pipe 17, as will be readily understood. The water in the return pipe 18 passes upward through the pipe 19 and downward through the pipe 20 60 to the boiler. Any steam or vapor which may accumulate in the expansion tank 6 passes through the branch pipe 22 and is absorbed or condensed by the cool water in the pipe 20.

65 Particular attention is directed to the fact

that the flow pipe which is connected to and extends from the boiler, is connected first with one of the radiators and is then connected successively with each of the other radiators, while the return pipe, which is connected to and extends from the boiler, is connected first with that radiator to which the flow pipe is connected with last, and the return pipe is then connected with the successive radiators to the first mentioned radiator. It is also to be noted that those portions of the flow and return pipes which are connected to the radiators, are arranged at a lower level than the radiators, the said portion of the return pipe being disposed 70 at a lower level than the said portion of the flow pipe, and cross-over connections being provided between the bottom of the said portion of the flow pipe and the said portion of the return pipe in advance of the radiator 75 connections. Thus, the hot water will be supplied with practical uniformity to the several radiators, without the liability of short circuiting any of the radiators, it being noted that the flow of the water in those 80 portions of the flow and return pipes which are connected to the radiators, is in the same direction.

In the modified form of invention shown in Fig. 3, the return pipe 18 is extended 85 downward as indicated at 19' to the lower 90 end of the boiler.

What is claimed as new is:

1. In a hot water heating system, a boiler, radiators, a flow pipe connected to and extending from the boiler and connected first with one radiator and thence successively with each of the other radiators, a return pipe connected to and extending from the boiler and connected first with that radiator to which the flow pipe is connected with last, the return pipe then being connected with the successive radiators to the first mentioned radiator, that portion of the return pipe which is connected to the radiators being disposed at a lower level than the corresponding portion of the flow pipe, the said portions of the flow and return pipes being arranged at a lower level than the radiators, and cross-over connections between the bottom of the said portion of the flow pipe and the said portion of the return pipe in advance of the radiator connections. 105 110 115

2. In a hot water heating system, a boiler, radiators, a flow pipe connected to and extending from the boiler and connected first with one radiator and thence successively with each of the other radiators, a return pipe connected to and extending from the boiler and connected first with that radiator to which the flow pipe is connected with last, the return pipe then being connected with the successive radiators to the first mentioned radiator, that portion of the return pipe which is connected to the radiators be- 120 125 130

ing disposed at a lower level than the corresponding portion of the flow pipe, the said portions of the flow and return pipes being arranged at a lower level than the 5 radiators, and cross-over connections between the bottom of the said portion of the flow pipe and the said portion of the return pipe in advance of the radiator connections, that end of the flow pipe remote from the 10 boiler being extended downwardly and attached to the return pipe beyond the radi-

ator connections, and that end of the return pipe remote from the boiler being extended upwardly and attached to the bottom of the flow pipe beyond the radiator connections. 15

In testimony that I claim the foregoing as my own, I have hereto affixed my signature in the presence of two witnesses.

ADOLF G. STAPEL.
